UNITED STATES PATENT OFFICE.

EDGAR E. GREVE, OF BELLEVUE, PENNSYLVANIA.

COMBINED AIR CHAMBER AND FLUID STRAINER FOR PUMPS.

Application filed April 6, 1927. Serial No. 181,592.

This invention relates to improvements in a combined air chamber and fluid strainer structure or device designed for use in connection with pumps.

5 The prime object of the present invention is, to provide a combined air chamber and strainer device of simple and efficient construction and of such a character that the removable strainer element thereof may be 10 readily applied to and removed from the structure.

Further objects of the invention are, to 15 provide a construction embodying a body portion made of a single casting and so designed that it may be readily cast in various sizes in order to meet the desired requirements as to the internal area of the device; a construction in which the integral cast body is formed with means for positioning a 20 removable strainer therein; a body member formed with two pairs of diametrically opposed openings respectively constituting fluid inlet and outlet openings and openings through which the replaceable strainer element may be passed; improved closing means 25 for the last mentioned openings; and a construction in which the replaceable strainer element is disposed between the fluid inlet and outlet openings in a plane at right angles 30 with the axes of said openings.

In the accompanying drawings, which 35 illustrate an application of my invention:

Fig. 1 is a side elevational view of a pump showing my invention applied thereto;

Fig. 2, a central vertical sectional view 40 showing the combined air chamber and strainer structure embodying my invention.

Fig. 3, a similar view taken on line III—III of Fig. 2;

Fig. 4, a horizontal sectional view taken 45 on line IV—IV of Fig. 2; and

Fig. 5, a plan view of a closing member employed for closing one of the openings in the body through which the replaceable 50 strainer is passed.

Referring to the drawings, 5 designates a pump structure which may be of any desired or preferred construction, and 6 designates, generally the combined air and strainer 55 structure embodying my invention, shown applied to the pump and in connection with an outlet fluid pipe 7.

The combined air and strainer device 6, as illustrated and as preferred, comprises an 55 integral cast body member having a fluid inlet opening or passage 8 and a fluid outlet

opening or passage 9. Inlet opening 8 is designed to be secured to the pump structure as particularly shown by Fig. 1, and the fluid outlet opening 9 is connected up with 60 the fluid discharge pipe 7. In addition to the passages 8 and 9 the body is formed with diametrically opposed openings or passages 10 and 11 disposed substantially at right angles to the openings 8 and 9; said openings 65 or passages 8 and 9, together with the openings 10 and 11, constitute two pairs of openings formed in the body.

Cover members 12 and 13 are respectively 70 provided for the openings 10 and 11 and are formed with a series of bolt receiving apertures 14 adapted to register, when the respective cover members are applied to the body structure, with threaded recesses 15 formed in annular flanges 16 surrounding the 75 respective openings 10 and 11; bolts 17 are employed for securing the cover members 12 and 13 to the said flanges 16. Each of the cover members is formed with an inwardly projecting member 18, designed, when the 80 parts are assembled, to maintain a strainer element 20 in the desired position within the structure.

Strainer element 20 is formed with apertures 21 and is disposed within the body in a 85 plane at right angles to the fluid entrance and exit openings. Said strainer element 20 is designed to be inserted and removed from the body through one or the other of the openings 10 or 11.

The interior of the body is divided into a 90 main air chamber 22 and an inner fluid chamber 23, by means of an integral wall 24; said wall 24 is formed with openings 25 and 26 into which the removable strainer element 20 95 is adapted to be placed and be maintained in the desired position within the body, i. e. in a plane at right angles to the axes of the fluid inlet and outlet passages 8 and 9.

From the above construction it will be apparent that the replaceable strainer element 20 may be readily placed within the interior 100 of the body through the openings 10 or 11 and that when so positioned on the interior wall 24, will be maintained in position by 105 means of the projecting members 18 respectively formed on the closure members 12 and 13. A removal of the strainer element 20 may be accomplished by removing one or both of the closure members 12 and 13.

What I claim is:

1. In an air chamber and strainer device

for pumps, the combination with a body having opposed fluid inlet and outlet passages and an air chamber, of a removable cylindrical strainer element disposed between said passages in a plane at right angles with the axes of said passages, said body having an opening in line with the strainer element, and closure-members for the last mentioned opening, said closure-members each provided with means for positioning and maintaining the strainer element in operative position.

2. In an air chamber and strainer device for pumps, the combination with a body having opposed fluid inlet and outlet passages and an air chamber, of a removable cylindrical strainer element disposed between said passages in a plane at right angles with the axes of said passages, said body having an opening in line with the strainer element, and closure-members for the last mentioned opening, said closure-members each having a projection thereon arranged to engage the strainer element.

3. In an air chamber and strainer device

for pumps, the combination with a body having two pairs of opposed openings and an air chamber, one pair of openings forming fluid inlet and outlet passages and the other pair of openings forming passages through which a strainer element may be positioned within the body, of a removable cylindrical strainer element disposed between the fluid inlet and outlet passages in a plane at right angles with the axes of said passages said air chamber disposed above and in a plane at right angles to the axis of the screen, and a closure-member for each of the other pair of openings.

4. An air chamber and fluid strainer device for pumps including an integral cast metal body formed with a pair of fluid inlet and outlet openings, said body having a second pair of opposed openings disposed in a plane substantially at right angles with the first pair of openings, and an air chamber disposed in a plane substantially at right angles with the second pair of openings.

In testimony whereof I affix my signature.
EDGAR E. GREVE.
